SWITCH.

1,264,852.

Specification of Letters Patent. Patented Apr. 30, 1918.

Application filed November 2, 1917. Serial No. 199,910.

To all whom it may concern:

Be it known that I, JAMES M. PHINOUS, a citizen of the United States, residing at Pamplin, in the county of Appomattox and 5 State of Virginia, have invented certain new and useful Improvements in Switches, of which the following is a specification.

This invention consists of a switch adapted to connect a side track or branch line to 10 a main line and wherein the main line rail sections are maintained in a continuous state thus avoiding the use of a frog whose points are subjected to wear and the use of which causes a gap that permit excessive pounding as the wheels of the vehicle pass over 15 the gap.

One object of the present invention is to provide a switch wherein the main line rail sections are maintained in a substantially 20 continuous state at the crossover.

Another object is to provide a bridging track element which serves to make a substantially continuous joint between the rails of the side track.

25 Still another object is to provide a frogless switch which has the side track rails slightly elevated at the point where they cross the main line rail sections, and connect the rail sections with an interposed 30 track element which is adapted to engage with a main line rail and be firmly held in position thereon.

A further object is to provide a track element hingedly mounted on a base plate 35 forming the connecting element and having a rail section on the upper surface and adjacent one edge, and a rail engaging lug on the under surface to coöperate with a main line rail section.

40 Broadly stated the invention comprises a frogless switch having an element hingedly secured to the base plate, said element being adapted to removably engage with a continuous rail section to complete an interrupted 45 section leading to a side track, the ends of which rail are slightly elevated adjacent the point of abutment, and means for moving the element and the points of the switch.

One practical form of construction and 50 assembly will be described and illustrated in the accompanying drawings, in which:

Figure 1 is a top plane view of the switch showing the several points of the invention,

Fig. 2 is a vertical sectional view through

the element that is employed at the cross-over, and 55

Fig. 3 is an enlarged detailed perspective view showing the element in its raised position to leave the main line clear.

In the preferred embodiment about to be 60 described the ties 5 may be such as those commonly employed in railroad construction. 6 and 7 are the main line track rail sections. The rail indicated at 6^a is adapted to be curved so that it will be continuous with the 65 side track rail 8. The main line rail 6 terminates in a switch point indicated at 9. The side track rail 10 terminates adjacent the main rail 6. As shown it is preferably provided with an angular face 11. 70

Between the main line rails 6 and 7 there is disposed a continuation 12 of the side track rail 10. This rail has its end adjacent the rail 6 provided with an angular end 13. Thus a gap is formed through which passes 75 the main rail 6. The rail 12 is provided at its other end with a switch point 14. The two switch points indicated at 9 and 14 may be connected by a bridle bar 15 adapted to hold them in proper spaced relation. 80

Other bridle bars may be used if desired. The switch points 9 and 14 are so arranged and formed that they may be placed to contact with the inner surface of either of the rails 6^a and 7. When the point 9 lies adjacent the rail 6^a the point 14 is spaced from the rail 7. Thus traffic passing over the main line rails will not be diverted into or on to the side tracks through the rails 8 and 10. The rails 10 and 12 are preferably 90 elevated a slight distance so that their tread surface is above the tread surface of the rail 6.

One means of maintaining this elevation is by employing a packing strip 16. 95 Any other means may be employed that will effectively hold the rail sections in their proper elevated position. The tie indicated at 5^a is preferably longer than the regular length and one end thereof projects sufficiently to have mounted thereon a bearing box 17. The box may be secured to the tie by any suitable means such as are indicated by the bolts 18.

The tie 56 is adapted to extend between 105 the main line and side track and extend sufficiently beyond so as to have mounted thereon a bearing box indicated at 19. The

bearing boxes 17 and 19 are preferably placed in alinement so that the crank shaft 20 may be rotatably mounted in the bearings. The box 19 may be secured to the tie 56 in any suitable manner.

One end of the crank shaft 20 may be provided with a bent end to form a crank 21. This crank is preferably formed upon the end which projects beyond the box 17.

- 10 One end of the connecting rod 22 may be formed to rotate on the bearing end of the crank 21 and be held thereon by any suitable means. The other end of the connecting rod 22 may be provided with a suitable 15 hole to coöperate with a throw bar 23 by means of a pivotal connection 24.

The other end of the throw bar 23 may be suitably connected with a bridle bar 15 as indicated at 25. This connection 25

- 20 may be any customary type. The other end of the crank shaft 20 where it projects beyond the bearing box 19 is preferably provided with an operating lever indicated at 26, which lever is provided with a 25 handle 27.

As shown the lever 26 comprises two plate portions lying in parallel planes that are joined by a portion angularly disposed with reference to both spaced portions. One 30 of the straight portions is adapted to provide a pivotal connection 28 with a throw bar 29 including a link. The other end of the throw bar is adapted to have a pivotal connection 30 with the element 31. The 35 element 31 serves as a substitute for a frog. A base plate 32 is adapted to extend from beneath the rail 8 and have its other end secured beneath the rail 6.

As shown the plate may be substantially 40 rectangular and be provided with the lugs 33 and 34. These lugs extend upwardly from the upper surface of the plate 32 and they are provided with holes which are in alinement with each other. These holes 45 serve to accommodate a pin 35 that is adapted to pass through each of the lugs and also through a lug portion 36 formed integral with the element 31. Thus a hinged type of joint is formed for the element 31.

- 50 The lugs 33 and 34 are so positioned that the element 31 is adapted to lie upon the track rail 6 and between the ends 11 and 13 of the rails 10 and 12. As these ends are angularly formed as before described the 55 element 31 has its corresponding corners angularly cut as indicated at 37 and 38. This is done so that when the element 31 lies upon the rail 6 a substantially continuous joint is formed between the rails 10 and 12. In order to more effectually provide for this the upper surface of the element 31 is formed with a rail section 39. This section 39 will thus form a tread surface and the wheels will ride over this point 65 with very little pounding.

In order that the element 31 may be properly maintained in its position upon the rail 6 the lug 40 is employed. As shown the lug is angularly disposed with reference to the longitudinal axis of the element. In 70 other words the axis of the lug 40 approximately corresponds to one of the diagonals of the element 31.

The lug 40 may be substantially rectangular in form and have one of its ends placed 75 adjacent the end 37 as shown in Fig. 3. When the element 31 lies upon the rail 6 the surface indicated at 41 will lie substantially in contact with the rail 6. In order to provide for the passage of the throw bar 80 toward the element 31 the rail 8 may be provided with a suitable opening indicated at 42.

When it is desired to operate the switch the handle 27 of the lever 26 is moved which 85 rotates the crank shaft 20 causing the crank 21 to change its position and move the switch points 9 and 14. At the same time the movement of the lever 26 will cause the throw bar 29 to move the element 31. When 90 the several devices are in the position shown in Fig. 1 the element 31 is in place so that a train approaching from the left will pass into the side track upon the rails 8 and 10. After the train has passed into this side 95 track which if desired may be a siding the lever 26 is operated in the reverse direction which will rotate the element 31 on the base plate 32 and place the point 9 adjacent the rail 6^a and the point 14 will be removed 100 from contact with the rail 7. The main line will then be open for a through traffic.

From the assembly of the several parts as described, it will be seen that the main line track rails are maintained in a substantially 105 continuous condition adjacent the point or crossover. Instead of the usual method of providing a gap and two points forming a portion of the frog, these points have been eliminated so far as the main line is concerned.

The gap that is formed between these rails at the points is filled in by the element 31 which provides a substantially continuous tread surface for the rails 10 and 12. 115

The element 31 may be formed of any suitable material but it is preferred that it be made to resist wear in the same way that the treads in the rails are treated. In case of repairs or renewals it will not necessitate 120 the tearing up of any portion of the track or road bed. To renew it is only necessary to withdraw the pin 35 and to release the connection 30. The element may then be easily withdrawn and a new one inserted. 125

What I claim is:—

In combination with a pair of main rails, siding rails, one of which intersects one of said main rails, a pair of switch points, one of said siding rails where it is intersected 130

- by one of said main rails having a gap or cutaway portion through which said intersecting main rail extends, thereby causing to be formed siding rail sections, the adjacent ends of said siding rail sections being oppositely beveled, a base plate having spaced lugs, a bridging frog plate pivoted between said lugs and designed to overlap the ball of the intersecting main rail to fill 5 in said gap, said frog plate having a section of rail ball on its upper surface extending from one of the outer corners of said frog plate to the other corner, the outer corners of said frog plate and the ends of the section of said ball being beveled correspondingly to and designed to become positioned adjacent said beveled ends of the siding rail sections, whereby said rail ball interconnects said siding rail sections, the under face
- of the frog plate being provided with an enlarged bracing lug diagonally disposed to engage the side of the ball of the intersecting main rail, whereby said frog plate is reinforced and the strains on its pivot relieved, when the frog plate is bridging the main rail, a shaft mounted in bearings of the ties and provided with cranks at both ends, said cranks having connections with the frog plate and the switch points respectively, and means for rocking said shaft for 10 simultaneously opening and closing the frog plate and the switch points respectively.
- In testimony whereof I affix my signature in presence of two witnesses.

JAMES M. PHINOUS.
